Lawrence J. Byer

By Robert H. Young J.W.

UNITED STATES PATENT OFFICE.

HERBERT O. RUSSELL, OF DETROIT, MICHIGAN, AND LAWRENCE J. EYLER, OF DAYTON, OHIO.

COCKING HANDLE FOR AERIAL GUNS.

Application filed April 18, 1922. Serial No. 555,019.

To all whom it may concern:

Be it known that we, HERBERT O. RUSSELL and LAWRENCE J. EYLER, citizens of the United States, residing respectively, at Detroit and Dayton, in the counties of Wayne and Montgomery and States of Michigan and Ohio, have invented certain new and useful Improvements in Cocking Handles for Aerial Guns, of which the following is a specification.

This invention relates to cocking handles for machine guns used on aircraft, the object in view being to provide a cocking handle that is easily adjustable for the purpose of changing the gun from a right hand to a left hand cocking gun. In the case of the Browning gun, it is necessary to change the handle of the gun to use the same flexibly, because of the fact that the gun should be controlled with the right hand leaving the left hand free for the cocking operation. On the Browning gun the cocking handle is normally on the right hand side. Due to the fact that the handle for the manipulation of the Scarff ring must be operated by the left hand, it is necessary that the gunner control his gun by maintaining a hold with his right hand upon the spade grip of the gun at all times. This has made it impossible to cock the gun with the right hand.

With the above and other objects in view, the invention consists in the novel construction, combination and arrangement herein fully described, illustrated and claimed.

In the accompanying drawings:

Figure 1, is a fragmentary side elevation of the gun showing the improved cocking mechanism applied thereto.

Figure 2, is a cross section taken on a line A. B. C. D. of Figure 1.

Fig. 3 is a detail view in side elevation of a portion of my device.

Referring to the drawings, (1) designates a link mounted upon the side of the gun and maintained in a horizontal position, or parallel to the longitudinal axis of the gun by means of a pin (2), which allows the bolt stud (3) to move back and forth in a rectilinear path with the bolt. (4) designates a link operating lever which is mounted upon the end of the rock shaft (5), the latter having its bearings in the rear stationary mounting trunnion of the gun. In assembling the mechanism, the shaft (5) is mount-

ed thru the bracket (6). The outer face of the bracket (6) contains a notch (7). A protrusion or projection 8 on the cocking handle is adapted to be fitted into this notch for the disassembling of the mechanism. This action holds the bolt of the gun in its extreme rearward position. In such position the removal of the bolt drive spring is rendered easy. A pin (9) on the bracket (6) forms a stop and limits the forward movement of the link (1). The operating handle (10) has upon the end thereof a ball handle (11) and has at the opposite end thereof a hardened plate (12) which carries a spring plunger (13). The function of this plunger is maintaining the cocking handle in any desired location. This is accomplished by the plunger dropping into the plunger seats (14) as shown by Figure 2. The entire cocking handle assembly as described, is fulcrumed upon the pin (15) extending transversely of the rock shaft (5) and forming a positive connection between the handle and rock shaft (5).

The mechanism herein above described is so designed that a complete disassembly operation may be accomplished by removing a cotter pin (16) which is used to prevent endwise movement of the rock shaft when the mechanism is in its operative position.

Having thus described our invention, we claim:

1. In combination with a machine gun, a cocking handle assembly embodying a rock shaft, a bolt-operating slide having a runway for a projection on the bolt of the gun, an arm on said shaft engaging said slide to draw the same back for cocking the gun, and a cocking handle on said shaft located on the opposite side of the gun from said slide-operating arm.

2. In combination with a machine gun, a cocking handle assembly embodying a rock-shaft, a bolt-operating slide having a runway for a projection on the bolt of the gun, an arm on said shaft engaging said slide to draw the same back for cocking the gun, a cocking handle on said shaft, and means for locking said handle in position to hold the bolt-drive spring under compression.

3. In combination with a machine gun, a cocking handle assembly embodying a rock-shaft, a bolt-operating slide having a runway for a projection on the bolt of the gun,

an arm on said shaft engaging said slide to draw the same back for cocking the gun, a cocking handle on said shaft, and means for limiting the movement of said handle to hold the parts in firing position.

4. In combination with a machine gun, a cocking handle assembly embodying a rock-shaft, a bolt-operating slide having a runway for a projection on the bolt of the gun, 10 an arm on said shaft engaging said slide to draw the same back for cocking the gun, a cocking handle on said shaft and a spring detent for holding said handle at predetermined points in its throw.

15 5. In combination with a machine gun, a cocking handle assembly embodying a rock-shaft, a bolt-operating slide having a runway for a projection on the bolt of the gun,

an arm on said shaft engaging said slide to draw the same back for cocking the gun, a 20 cocking handle pivoted on a transverse axis on said shaft, and means for holding said handle at a point in the throw thereof.

6. In combination with a machine gun, a 25 cocking handle assembly embodying a rock-shaft, a bolt-operating slide having a runway for a projection on the bolt of the gun, an arm on said shaft engaging said slide to draw the same back for cocking the gun, a cocking handle on shaft, and means permitting 30 the entire cocking handle assembly to be detached from the gun.

In testimony whereof we affix our signatures.

HERBERT O. RUSSELL.
LAWRENCE J. EYLER.
